[57] **CLAIM**

The ornamental design for a combined bracket and locking hook unit for holding truck tire chains, as shown and described.

DESCRIPTION

FIG. 1 is a top plan view of a combined bracket and locking hook unit for holding truck tire chains in open condition, showing my new design;

FIG. 2 is a side elevational view thereof;

FIG. 3 is a front elevational view thereof;

FIG. 4 is a rear elevational view thereof; and

FIG. 5 is a bottom plan view thereof.

The broken line showing of the padlock in FIGS. 2 and 4 is for illustrative purposes only.
